UNITED STATES PATENT OFFICE.

ERNEST GOTHLBERG, OF JERSEY CITY, NEW JERSEY.

DESIGN FOR AN ORNAMENTAL TRIMMING FOR GAS AND ELECTRIC-LIGHT FIXTURES.

SPECIFICATION forming part of Design No. 33,555; dated November 13, 1900.

Application filed October 11, 1900. Serial No. 32,790. Term of patent 7 years.

To all whom it may concern:

Be it known that I, ERNEST GOTHLBERG, a citizen of the United States, residing at Jersey City, in the county of Hudson and State of New Jersey, have invented and produced a new and original Design for Ornamental Trimmings for Gas and Electric-Light Fixtures, of which the following is a specification, reference being had to the accompanying drawings, forming part thereof, in which—

Figure 1 is a side elevation of a trimming for gas and electric-light fixtures embodying my design, and Fig. 2 a cross-section on the line 2 2 thereof.

In the drawings forming part of this specification I have shown at *a* a hollow conical body designed as a trimming for gas and electric-light fixtures, and the leading or material feature of my design consists of the hollow body *a*, provided with the spirally-arranged grooves *b*, countersunk in the walls of said body, said grooves being larger at one end than at the other and the upper ends thereof being directed upwardly or toward the larger end of said body and the smaller end thereof downwardly or toward the apex thereof, which is cut away, as shown at *c*.

The alternate grooves *b* are longer than the others, the upper or larger ends thereof terminating in a horizontal plane below that in which the other or longer grooves terminate, and all of said grooves are curved from the upper ends thereof to the right and downwardly and spirally, as clearly shown in Fig. 1.

My design may be applied to double conical trimmings of the class shown or to trimmings having semispherical ends or to other designs.

Having fully described my invention, I claim as new and desire to secure by Letters Patent—

The design for an ornamental trimming for gas and electric-light fixtures, as herein shown and described.

In testimony that I claim the foregoing as my invention I have signed my name, in presence of the subscribing witnesses, this 9th day of October, 1900.

ERNEST GOTHLBERG.
